UNITED STATES PATENT OFFICE

159,258

CLOCK

Henry Engel, Los Angeles, Calif.

Application November 22, 1949, Serial No. 6,195

Term of patent 7 years

(Cl. D42—7)

To all whom it may concern:

Be it known that I, Henry Engel, a citizen of the United States, residing in Los Angeles, county of Los Angeles, State of California, have invented a new, original, and ornamental Design for a Clock, of which the following is a specification, reference being had to the accompanying drawings, forming a part thereof.

Figure 1 is a front elevational view of a clock showing my new design;

Figure 2 is a rear elevational view of Figure 1; and

Figure 3 is a top plan view of the clock.

I claim:

The ornamental design for a clock, substantially as shown.

HENRY ENGEL.
